UNITED STATES PATENT OFFICE

OTTO CARTER BERRY, OF INDIANAPOLIS, INDIANA, ASSIGNOR TO THE WHEELER-SCHEBLER CARBURETOR CO., OF INDIANAPOLIS, INDIANA, A CORPORATION OF INDIANA

CARBURETOR

Application filed April 27, 1923. Serial No. 635,013.

It is well known among carburetor engineers that an internal combustion engine which receives its supply of explosive mixture through a liquid-fuel carburetor requires a mixture much richer in fuel in starting cold than is necessary for best performance after it is thoroughly warmed up.

It is also well established that the mixture required for maximum power is considerably richer than that for maximum economy.

It is also well known that when the throttle of a carburetor is suddenly opened wider, at least a portion of the gasoline falls behind the air in its passage through the intake manifold of the engine and collects on the manifold walls. This results in a temporarily impoverished mixture at the engine cylinders, even though the proportions are maintained at the carburetor, and this is often accompanied by a temporary lack of power on the part of the engine or even by the stalling of the engine.

It is also well known that in the case of a carburetor having an air-valve, unless adequate means are provided to prevent it, the air-valve will flutter when the engine is running at low speeds under heavy load, and that this fluttering of the air-valve will upset the proportions of the fuel and air mixture.

For these and other reasons, unless special provisions are made in the design of the carburetor, the use of lean and economical mixtures will result in operating difficulties, among which are the following:

(1) The engine will be hard to start when it is cold.

(2) The performance of the engine will be poor and difficult to control during the warming-up period.

(3) The engine will be unable to respond immediately and positively to a sudden demand for greater power, especially when it has previously been running at a low speed.

(4) The engine will lack power under a heavy pull, when it is so adjusted as to give maximum economy under ordinary driving conditions.

(5) The engine will be unable to perform

properly at low speed under a heavy load.

It is the object of my invention to provide means for obviating all these difficulties, and to produce a carburetor that will meet all the following requirements:

55

(1) Furnish a well-atomized mixture of proper richness through a very wide range of rates of flow of the air through the carburetor.

60

(2) Furnish a mixture of such proportions as to produce maximum economy when the engine is running at part throttle.

65

(3) Furnish a mixture of such richness as to produce maximum power when the engine is running with a wide-open throttle.

70

(4) Furnish a temporarily enriched mixture during periods of acceleration, whether the acceleration starts from low or high engine-speeds.

75

(5) Provide a means that can be operated from the driver's seat to enrich the mixture throughout the range for starting and for gradually reducing the amount of such enrichment during the period of warming up.

80

(6) Provide a means of damping out the fluttering of the air valve.

The accompanying drawings illustrate my invention, and show a preferred embodiment thereof. In such drawings: Fig. 1 is an elevation of a carburetor embodying my invention; Fig. 2 is a plan thereof; Fig. 3 is a vertical longitudinal section on the line 3-3 of Fig. 2; Fig. 4 is a transverse section on the line 4-4 of Fig. 3; Fig. 5 is a partial section illustrating one form of the fuel-metering mechanism; Fig. 6 is a partial vertical longitudinal section showing the position of the metering mechanism when the auxiliary-air valve is partly open; Fig. 7 is a partial section similar to Fig. 5, but with the parts shifted to show the effect on the metering mechanism of throwing the fulcrum-arm to the position for a rich mixture, as when the dash-control is pulled out for starting; Fig. 8 is a transverse section on the line 8-8 of Fig. 6; Fig. 9 is a partial vertical section showing one arrangement for obtaining an idle adjustment; Fig. 10 is a transverse section on the line 10-10 of Fig. 9; Fig. 11 is a ver-

100

tical section through the auxiliary-air valve showing the metering orifice for the accelerating device; and Fig. 12 is a fragmentary section on the line 12—12 of Fig. 4.

My carburetor has a main body 1 and a float bowl 2. Air may enter the carburetor in two ways. It may enter (Fig. 3) through the fixed-air passageway, made up of an inlet 3, a passage 4, and a venturi 5, picking up and atomizing the gasoline at the end of a gasoline nozzle 6; and, when this passageway is not large enough, by a variable auxiliary-air passageway 8 having at its entrance a spring-seated air valve 7 which will be depressed to allow such air to enter through this auxiliary-air passageway 8 as is required. In either case, the air passes through the body of the carburetor past a throttle 9 and out through a mixture-discharge opening 10.

The gasoline enters the float-bowl 2 through a strainer cap 11 past a float-needle 12, and the gasoline level is regulated by a float 13 operating said float-needle. From the float-bowl, the gasoline is drawn through the passageway 14 (Figs. 4, 5, and 12), past a tapered needle or metering-pin 15, and is metered at the circular orifice 16 at the top of the passageway 14. It then passes through a cross-drilled hole 17 (Figs. 4 and 12) and the gasoline-nozzle 6 (Fig. 3) into the air stream in the throat of the venturi 5, and thence on through the carburetor with the air. The gasoline needle 15 may have a long cylindrical section 18 (Fig. 5) by which it is guided, so that it is always concentrically located in the metering orifice 16.

As the rate of flow of air through the carburetor is changed, the air and gasoline must be kept in the proper proportions. This is done as follows: To the auxiliary-air-valve 7 is fixed an arm 19 (Fig. 3) which is pivoted to one end of a proportioning-lever 20. This proportioning-lever passes through and has a close sliding fit in a trunnion-block 21, which in turn is pivotally mounted on a fulcrum-pin 22 in the lower end of a pivotally adjustable fulcrum-arm 23. On the other end of the proportioning-lever is another sliding trunnion-block 21^a, which is pivotally attached to the top of the metering-pin 15 by a pin 24, (Fig. 5). Thus as the air-valve 7 moves, the proportioning-lever turns about the pin 22 and gives to the metering-pin 15 a motion that is in proportion to that of the air-valve; and the proportioning-lever slides slightly in the trunnion-blocks 21 and 21^a as required in this movement.

The pressure differential causing the air to flow past the air-valve, and the suction causing the fuel to flow past the metering-pin, bear substantially the same relation to each other at all rates of flow of the air

through the carburetor. Theoretically, the flow of air and the flow of fuel follow, fundamentally, the same law of increase with an increase in pressure differential, and the lift of the metering-pin is in direct proportion to the air-valve motion. Thus the ratio of fuel to air might be expected to remain substantially constant with a straight-tapered metering-pin and a straight-tapered auxiliary-air passageway. Actually, these laws are not accurately followed, however, and to maintain a constant mixture-ratio, or to obtain any desired variation in this mixture-ratio with a change in the rate of air-flow, it is usually necessary to vary from a straight-taper the shape of either the metering-pin or the auxiliary-air passageway. I usually change the latter, as it is so much larger and therefore so much less sensitive to small changes; and use a straight-tapered metering-pin.

The method of procedure in working out the proper shape for the inner surface of the auxiliary-air passageway is as follows: Tests are run at a large number of different rates of flow of air through the carburetor, and a record made of the weight of air and of fuel that passed during each test. From these figures the ratio of the fuel to air in the mixture is computed for each rate of air flow. Suppose now that the mixture is found to be too rich at the particular position of the air-valve shown in Fig. 6. The inner surface 25 of the auxiliary-air passageway is then hollowed out so as to provide a larger opening past the valve in this position, until the mixture is brought to the required proportions. When the mixture is too lean the reverse action is taken. By this means the richness of mixture obtained at each and every flow-rate is brought to the desired point and the carburetor is made to follow the requirements of the engine with great accuracy.

There are a number of methods of measuring the amount of air and fuel passing through a carburetor and of simultaneously determining the excellence of the performance of the engine. These methods are well understood by engineers and any one of them may be used when working out the proper shape of the air funnel. Engineers are also familiar with the methods of determining whether the mixture is richer or leaner than they desire for any given running conditions, or whether it is just right. In determining the proper shape of the inner surface of the air funnel it is therefore necessary for the engineer skilled in this art to determine by test the mixture requirement of an engine at each of a large series of different rates of air flow through the carburetor, and then by the above mentioned experimental means, determine the shape of

the air funnel required to produce the desired mixture at each rate of air flow.

The taper of the metering-pin 15 is chosen to give the desired mixture when the fulcrum-arm 23 is substantially at right angles with the proportioning-lever 20 when the auxiliary-air valve is closed, so that a small motion of the trunnion block 21 in either direction will not change the position of the metering-pin 15 and thus affect the idle adjustment. Shifting the trunnion block 21 toward the air-valve, as indicated in Fig. 5, will cause the metering-pin to move farther for a given air-valve motion and result in an enriched mixture at all rates of air-flow.

In order to provide a wide range of flow-rate capacities, the fixed-air opening through the venturi 5 is made small, and the auxiliary air-valve 7 is made large.

The seating spring 26 of the air-valve 7 is made strong enough so that during operation the vacuum in the body of the carburetor will be sufficient to atomize the fuel at the throat of the venturi 5, even at very low rates of air flow.

A dash-pot piston 28 (Fig. 3) in a fuel dash-pot 27 is connected to the air-valve 7, and serves a double purpose—to keep the air-valve from fluttering, and also to aid in accelerating with a lean mixture. The former of these two purposes is obtained by an obvious dash-pot effect. The latter is accomplished as follows: When the dash-pot piston 28 is depressed, it forces fuel up through a passageway 29 in the piston-stem 30 and into the interior of a hollow nut or chamber 31; which is higher than the fuel level in the float bowl 2, and above the air-valve 7. The size of the passageway 29 is experimentally determined so that in practice it will deliver a satisfactory amount of fuel to the chamber 31. The chamber or nut 31 may in some cases have a vent 32. The gasoline then flows out through a metering-orifice 33 (Figs. 3, 6, and 11) and through a passageway 34 (Fig. 6) to a point 35 at the edge of the air-valve 7, where it is thoroughly atomized as it enters the air stream. In this way the mixture is temporarily enriched during periods of acceleration, by temporarily supplying gasoline to the air passing the air-valve 7.

A check-valve 36 (Fig. 6) keeps the gasoline from returning to the dash-pot 27, and prevents air from getting under the dash-pot piston 28 while it is being raised by the spring 26.

It is desirable to have the air-valve 7 open more slowly than it closes. This is accomplished by having the thin circular disk 37 placed below the holes 38 in the piston 28, and capable of moving a very short distance vertically relative to such piston. This makes an effective check-valve.

During wide-open-throttle running at

very low speeds, the air velocities through the carburetor are so low that the fuel striking the walls will trickle down and tend to collect in the bottom of the body. When the speed is subsequently increased, this collection of liquid fuel will be picked up by the air stream more or less suddenly, making the mixture temporarily too rich. This is commonly called loading. To prevent this, the floor of the body 1 is caused to slope toward the venturi 5 from all sides, to form a sump 39. Small holes 40 are drilled into the venturi 5 opposite the bottom of this sump 39, and open into the inside of the venturi just above the throat. The suction of the venturi is high at this point, and draws in any fuel that collects in the sump 39, atomizing it and re-introducing it into the air stream.

A small percent of the atomized fuel tends to collect on the walls of the venturi and leave the upper edge in droplets. To prevent the formation of these droplets, the upper end of the venturi is turned inward in a sharp edge 41, which re-introduces this fuel into the air stream thoroughly atomized.

The enriched mixture for full power at open throttle is obtained as follows: The fulcrum-arm 23 which supports the fulcrum-pin 22 is fastened to the fulcrum-arm-shaft 42. This shaft 42 passes through the body-casting to the outside. Arms 43 and 44 (Fig. 1) are fastened to this shaft 42 on its outer end. The arm 44 is held against an adjusting-screw 45 in a lug 46 by a spring 46a. The position of the screw 45 affects the position of the fulcrum-pin 22, and so governs the richness of the mixture throughout the range of the carburetor at partly closed throttle positions. The arm 43 is acted on by a cam 47 on the throttle-shaft 48, in such a way that when the throttle 9 is wide open the lever 43 is depressed, the trunnion-block 21 and fulcrum pin 22 are moved toward the air-valve, and in consequence the fuel-needle is given a greater lift for a given air-valve motion, and the mixture is made richer. The amount of this enrichment and the point in the throttle movement where it starts may be changed by adjusting the screw 50.

The short arc of movement of the fulcrum pin 22 about the shaft 42 in this adjustment is fairly close to a straight line parallel to the proportioning lever 20 when the air-valve 7 is closed, so that then such shifting of the fulcrum pin does not greatly vary the position of such lever or of the metering pin 18.

The low-speed adjustment is made as follows:—

The shaft 42 passes through a rotatably adjustable eccentric 51 (Figs. 9 and 10) which is fastened to an adjusting device 52

(Figs. 1 and 9). Moving the adjusting device 52 will turn the eccentric 51 to raise or lower the shaft 42, thus raising or lowering the fuel-metering pin 15 for any given position of the air-valve 7, and so making the idle mixture richer or leaner respectively without materially changing the proportionate part of the air-valve motion transmitted to said metering-pin. It is therefore possible to change the idle adjustment without greatly affecting the mixture at higher rates of flow. This idle adjustment thus varies the relative positions of the fuel-valve and its seat for a given air-valve position. The movement of the fulcrum-arm-shaft 42 obtained by this idle adjustment is fairly close to perpendicular to the proportioning lever 20, to minimize the shifting which it produces of the fulcrum-pin 22 along such proportioning lever.

To obtain the rich mixture for starting a cold engine, a dash adjustment is provided which connects to the arm 43 through a wire 53, (Fig. 1). Pulling down on the wire 53 will turn the fulcrum-arm 23 and shift the trunnion-block 21 and fulcrum-pin 22 toward the air-valve 7 to increase the lift of the fuel-needle 15 for a given opening of such air-valve; and (because of the relatively large angular extent of such turning) even to cause a considerable lift of such needle-valve while the air-valve 7 is still on its seat, which results effectively in an enriched starting mixture, as desired.

I claim as my invention:—

1. In a carburetor, the combination with a casing having a mixing chamber, a throttle valve, and a throttle shaft, of a fuel nozzle discharging fuel which is delivered into said mixing chamber, a metering-pin for controlling the quantity of fuel delivered by said nozzle, an air-valve, lever-means for transmitting motion from said air-valve to said metering-pin, a fulcrum for said lever-means, said mixing chamber having an air-inlet opening with which said air-valve operates, and means operated from said throttle-shaft for changing the position of said fulcrum to enrich the mixture when said throttle-valve approaches wide-open position.

2. In a carburetor, the combination of a mixing chamber, a throttle, a fuel nozzle discharging fuel which is delivered into said mixing chamber, said mixing chamber being provided with an air-inlet opening, an air-valve tending to close said air-inlet opening but movable to vary its effective size, a fuel-valve controlling the fuel discharged from said fuel nozzle, means interconnecting said fuel-valve and said air-valve so that the former is actuated by movements of the latter, and means operated by said throttle for varying the proportionate part

of said air-valve movement which is transmitted by said means to said fuel-valve.

3. In a carburetor, the combination of a mixing chamber, a throttle, a fuel nozzle discharging fuel which is delivered into said mixing chamber, said mixing chamber being provided with an air-inlet opening, an air-valve tending to close said air-inlet opening but movable to vary its effective size, a fuel-valve controlling the fuel discharged from said fuel nozzle, a lever interconnecting said fuel-valve and said air-valve, a fulcrum on which said lever is mounted, a fulcrum-arm which carries such fulcrum, a fulcrum-arm shaft about which said fulcrum-arm rotates, an operating arm on said fulcrum-arm shaft, and a cam operated by movements of said throttle for actuating said operating arm to enrich the mixture when said throttle is at or near wide-open position.

4. In a carburetor, the combination of a mixing chamber, a fuel nozzle discharging fuel which is delivered into said mixing chamber, said mixing chamber being provided with an air-inlet opening, an air-valve tending to close said air-inlet opening but movable to vary its effective size, a fuel-valve controlling the fuel discharged from said fuel nozzle, a lever interconnecting said fuel valve and said air-valve, a fulcrum on which said lever is mounted, and a plurality of operating devices for independently shifting the location of said fulcrum.

5. In a carburetor, the combination of a mixing chamber, a throttle, a fuel nozzle discharging fuel which is delivered into said mixing chamber, said mixing chamber being provided with an air-inlet opening, an air-valve tending to close said air-inlet opening but movable to vary its effective size, a fuel-valve controlling the fuel discharged from said fuel nozzle, a lever interconnecting said fuel-valve and said air-valve, a fulcrum on which said lever is mounted, means for operating said throttle, and means for shifting the position of said fulcrum by the operation of the throttle and independently of the throttle.

6. In a carburetor, the combination of a mixing chamber, a fuel-valve and an air-valve controlling respectively quantities of fuel and air delivered to said mixing chamber, a lever interconnecting said two valves, a fulcrum for said lever, and two separately operable means for shifting said fulcrum substantially lengthwise of and substantially transverse to said lever respectively.

7. In a carburetor, the combination of a mixing chamber, a fuel-valve and an air-valve controlling respectively quantities of fuel and air delivered to said mixing chamber, a lever interconnecting said two valves, a fulcrum for said lever comprising a pivoted sleeve in which said lever is slidably

mounted, and a plurality of adjustable carrying means for said sleeve for shifting it substantially lengthwise and crosswise of said lever.

8. The combination set forth in claim 7, wherein said fulcrum-carrying means comprises a pivoted arm to which a sleeve is pivoted, an eccentrically adjustable bearing for said pivoted arm, and means for turning said arm to adjust said fulcrum.

9. In a carburetor, an accelerating device made up of a combination of a fuel dash-pot chamber, an auxiliary fuel chamber above the fuel level of the carburetor, a passageway from said dash-pot chamber to said fuel chamber, an air-valve, a piston in said dash-pot chamber so actuated by an opening motion of said air-valve as to force fuel into said elevated fuel chamber, and a passageway provided with a metering orifice and leading from said elevated fuel chamber to the air stream entering the carburetor.

10. In a carburetor, an accelerating device made up of a combination of a fuel dash-pot chamber, an air-valve, an auxiliary fuel chamber above said air-valve, a passageway leading from said dash-pot chamber to said elevated chamber, a check valve in said passageway, a piston in said dash-pot chamber so actuated by an opening movement of said air-valve as to force fuel into said elevated fuel chamber, and a passageway provided with a metering orifice and leading from said elevated fuel-chamber to the edge of said air-valve.

11. In a carburetor, the combination of a mixing chamber, a throttle, a fuel nozzle discharging fuel which is delivered into said mixing chamber, said mixing chamber being provided with an air inlet, an air-valve tending to close said air-inlet but movable to vary its effective size, said air inlet having a funnel-like interior surface specially shaped to regulate the proportionate amount of air flowing at each consecutive position of said air-valve, a fuel-valve controlling the fuel discharged from said fuel nozzle, means interconnecting said fuel-valve and said air-valve so that the former is actuated by movement of the latter, and means controlled in accordance with adjustment of said throttle for varying the proportionate part of said air valve movement which is transmitted by said means to said fuel valve.

12. In a carburetor in combination, a mixing chamber, a fixed air inlet to said mixing chamber, a variable air inlet to said mixing chamber comprising a valve which by its movement in a contoured passageway adjusts the effective area thereof, a reservoir for fuel, a nozzle supplied from said reservoir and feeding into said fixed air inlet, mechanical means to modify the flow of fuel from said nozzle mechanically connected

with said air valve so that an increased air flow increases the fuel flow, a throttle to control the efflux of mixture from said carburetor, and means operated by said throttle to vary the ratio of movement of said air valve to said fuel flow modifying means.

In witness whereof, I have hereunto set my hand at Indianapolis, Indiana, this 24th day of April, A. D. one thousand nine hundred and twenty three.

OTTO CARTER BERRY.
